United States Patent Office

Des. 227,198
Patented June 12, 1973

227,198

SANDAL

Tatsuo Fukuoka, 3, 3-ban, 2-chome, Shin-Minami-Fukushima, Tokushima, Japan

Filed Jan. 31, 1972, Ser. No. 222,462

Claims priority, application Japan Dec. 7, 1971

Term of patent 14 years

Int. Cl. D2—04

U. S. Cl. D2—283

FIG. 1

FIG. 2

FIG.4

FIG. 5

FIG. 6

FIG. 1 is a top plan view of a sandal showing my new design;

FIG. 2 is a side elevational view thereof;

FIG. 3 is a bottom plan view;

FIG. 4 is a side elevational view of the side opposite that shown in FIG. 2;

FIG. 5 is a front elevational view; and

FIG. 6 is a rear elevational view.

I claim:

The ornamental design for a sandal, substantially as shown.
